KEY FOR LUGGAGE LOCKS

Erwin Kalla, West Pittsburg, Pa., assignor to Reliable Luggage, Inc., West Pittsburg, Pa., a corporation of Pennsylvania

Application June 5, 1957, Serial No. 46,490

Term of patent 14 years

(Cl. D50—4)

Fig. 1.

Fig. 2.

Fig. 1 is a front elevation of a key for luggage locks, showing my new design; and

Fig. 2 is a sectional view along line 2—2 of Fig. 1.

The dominant features of my key design reside in the portions shown in full lines.

I claim:

The ornamental design for a key for luggage locks, as shown and described.
